UNITED STATES PATENT OFFICE.

MAURICE J. STACK, OF COHOES, NEW YORK, ASSIGNOR TO BRINTNALL MANUFACTURING COMPANY, INC. OF DELAWARE, OF WILMINGTON, DELAWARE, A CORPORATION OF DELAWARE.

APPARATUS FOR FILLING PIPING TOOLS.

Application filed August 23, 1927. Serial No. 214,979.

My invention relates to the art of preparing pleated upholstery cushions and it especially has for its object the provision of a new and useful apparatus by the use of which a combined bat-containing and stuffing tool may be quickly loaded and prepared for use in stuffing the piping or pleats of cushions, seats, backs, etc. used in upholstering automobiles and other vehicles.

10 Further, it is an object to provide an apparatus for holding a roll of batting and feeding the batting onto a shelf over a table on which the combined bat-containing and stuffing tool may be laid while it is being 55 filled, the feeding operation from the roll to the table being under control of the attendant operator.

Further it is an object of this invention to provide the table with means always to locate the receiving section of the tool at a definite place on the table and to provide means whereby the back section may be almost automatically slid into place in said tool section.

25 Other objects will in part be obvious and in part be pointed out hereinafter.

To the attainment of the aforesaid objects and ends, my invention consists in the novel details of construction, and in the combination, connection and arrangement of parts hereinafter more fully described and pointed out in the appended claims.

In the accompanying drawing in which is illustrated a preferred embodiment of my invention,

Figure 1 is a top plan view of the same. Figure 2 is a front elevation thereof.

Figure 3 is an end elevation.

40 Figure 4 is a cross section on the line 4—4 of Figure 2.

Figure 5 is an enlarged detail perspective view of portions of the two halves which compose the combined bat-container and stuffing tool, separated.

45 Figure 6 is an end elevation of the parts shown in Figure 5, assembled.

Figure 7 is a perspective view of one of the combined bat-container and stuffing tools assembled.

50 In the drawing, in which like numerals of reference indicate like parts in all the figures, the stand for supporting the roll of continuous bat is composed of side frames 1

spaced apart and secured by tie bolts and spacers 2. On the upper end of the stand is mounted the roller-bearing brackets 3 which carry the bearing rollers 4 on which the bobbin spindle 5 rests. Side plates 6 may be provided to prevent the bat in the roll from slipping laterally.

The frame also carries brackets 7 which have standards 8 in which the lower and upper feed roller bearings 9 and 10 respectively are located. The said rollers are provided with shafts 11 and intermeshing gears 12 so that the rollers may turn in unison.

13 designates a drive shaft having fast and loose pulleys 14 and 15 over which the driving belt 48 runs. The drive shaft 13 is mounted in suitable bearings 16 on the frame members 1 and carries a pinion 17 that meshes with an idler gear 18 on a stub shaft 19, the idler gear 18 in turn meshing with the gear 12 of the lower feed roller 20.

The driving belt 48 is shifted from one pulley 14 to the other pulley 15 and vice versa by a mechanism hereinafter called a controller. It consists of belt shifting fingers 21 mounted on a slide bar 22 that is carried in suitable bearing brackets 23 and 80 is operated by a bell crank 24 mounted at 25 and connected with a treadle lever 27 by means of a connecting rod 26, the lever 27 having its foot engaging part 29 projected beneath the table into position for convenient operation by the attendant. The lever 27 is mounted at 28 in any suitable way.

The table 30 carries a bracket 31 at the side opposite that where the stand is located and on this bracket 31 is a stub shaft 33 on which a belt roller 32 is journaled, a similar roller 32^a being journaled on the shaft 33^a that is mounted in suitable bearings on the brackets 7. Around the rollers 32 and 32^a is an endless conveyor belt 35 constituting a shelf above the top of the table 30.

The conveyor is driven by means of a gear 36 on the shaft 34 of the roller 32^a, which gear 36 meshes with an idler gear 37 that in turn meshes with the gear 12 of the lower rollers 20.

The table 30 is preferably provided with a tool receiving groove or recess 38 shaped 105 to fit the lower half 41 of the combined bat-

containing and stuffing tool 41 and 42, the sections of which when assembled overlap slightly and have centering pins 43.

If desired, a chute or guide plate 39 suitably supported at 40 may be provided to assist in delivering the bat section 47 from the belt 35 to the tool section 41, see Figures 1 and 2. The tool parts 41 and 42 when assembled are held together by a band 10 or ring 44 that is adapted to be slipped onto the tool from one end.

The roll of endless bat is indicated by 45 and it is preferably separated into bat sections 47 by weakening portions 46.

15 In using my present invention the roll of batting is placed on the stand and the end threaded between the rollers 20. The operator then takes a batting tool, places one-half of it on the table with its open side 20 uppermost and presses the treadle portion 29 to shift the belt onto the fast pulley thereby setting the rollers 20 and endless belt in motion. Upon a bat section 47 being fed onto the belt, the operator severs the section 25 from the next succeeding one and slips the section of batting down and over edge-wise into the trough-like tool section 41. He then places the other half of the container in position, slips on the ring or band 30 44 and is then ready to repeat the operation with the next tool and bat section. It is, of course, understood that the operator can stop and start the feed by manipulation of the treadle lever at his convenience. It will be 35 obvious that the bat section, when it passes the rollers 20, is laid flatwise on the belt 35 (shelf) while it must be turned through a quarter revolution to enter edge-wise into the trough-shaped section 41 of the tool. 40 By the provision of the chute or guide plate 39 this operation is almost automatically accomplished since all that the attendant need do is to sever the advance section 47 of the bat from the following section and slide the bat edge-wise off the belt 35 onto the chute 39 where it will be turned over edge-wise and be thus delivered to the receiving tool section.

45 By the use of my apparatus and the use of a large number of tools it is possible to charge the tools with bat sections at the bat factory and stack the tools side by side and in superposed layers in suitable shipping cartons or boxes. The tools so charged are then delivered to the customer who uses them in the ordinary way for piping the bats and returns the tool section to the bat factory for recharging. Or, the charging of the tools can be accomplished by the use 55 of my apparatus located at the customer's factory so that as fast as a tool is charged by one operator another may use it to pipe a bat. By the use of my apparatus the operation of charging the piping tool and its use 60 in piping the bat is expedited.

Instead of driving the belt 35 positively by power the belt carrying rollers 32 and 32 may run idle and the movement of the belt obtained by the simple act of feeding the material onto the belt by the rollers 20, 70 the friction of the material in engagement with the belt causing the belt to travel with the material, though I prefer to drive the belt by positive driving connection with the source of power either through the feed rollers' ears or in some other suitable way. 75

80 From the foregoing description, taken in connection with the accompanying drawing, it is thought the construction, operation and advantages of my invention will be clear to those skilled in the art to which it relates.

What I claim is:

1. In apparatus of the class described, a table, a shelf located above the table, a bat holding stand adjacent the table, means for feeding a continuous bat from said stand onto said shelf, said table having provisions to receive a bat receiving tool into which a bat section from the shelf may be placed. 90

2. In apparatus of the class described, a table, a shelf located above the table, a bat holding stand adjacent the table, means for feeding a continuous bat from said stand onto said shelf, said table having provisions to receive a bat receiving tool into which a bat section from the shelf may be placed, and means for directing the bat section from said shelf into the tool section. 95

3. In apparatus of the class described, a table, a shelf located above the table, a bat holding stand adjacent the table, means for feeding a continuous bat from said stand onto said shelf, said table having provisions to receive a bat receiving tool into which a bat section from the shelf may be placed, and means controlling said feeding means from a place adjacent the table in convenient position for the operator. 105

4. In apparatus of the character described, a stand, means to sustain a roll of continuous batting on said stand, feed rollers mounted on the stand, means to operate said rollers, a table adjacent said stand, an endless conveyor to receive the bat from the feed rollers, the receiving flight of the conveyor being located above the table. 115

5. In apparatus of the character described, a stand, means to sustain a roll of continuous batting on said stand, feed rollers mounted on the stand, means to operate said rollers, a table adjacent said stand, an endless conveyor to receive the bat from the feed rollers, the receiving flight of the conveyor being located above the table, and means to drive said conveyor in unison with said feed rollers. 120

6. In apparatus of the character described, a stand, means to sustain a roll of continuous batting on said stand, feed roll- 130

ers mounted on the stand, means to operate said rollers, a table adjacent said stand, an endless conveyor to receive the batting from the feed rollers, the receiving flight of the conveyor being located above the table, means on said table to position a bat-holding tool for the reception of a bat section taken from the conveyor.

7. In apparatus of the character described, a stand, means to sustain a roll of continuous batting on said stand, feed rollers mounted on the stand, means to operate said rollers, a table adjacent said stand, an endless conveyor to receive the batting from the feed rollers, the receiving flight of the conveyor being located above the table, said rollers' operating means comprising a driving means and a controller therefore, said controller being operable by an attendant standing at the table in position to fill said tool section.

8. In apparatus of the character described, a stand, means to sustain a roll of continuous batting on said stand, feed rollers mounted on the stand, means to operate said rollers, a table adjacent said stand, an endless conveyor to receive the batting from the feed rollers, the receiving flight of the conveyor being located above the table, means on said table to position a bat-holding tool for the reception of a bat section taken

from the conveyor, said positioning means comprising a recess in the table to hold a tool with its open side uppermost.

9. In apparatus of the character described, a stand, means to sustain a roll of continuous batting on said stand, feed rollers mounted on the stand, means to operate said rollers, a table adjacent said stand, an endless conveyor to receive the batting from the feed rollers, the receiving flight of the conveyor being located above the table, means on said table to position a bat-holding tool for the reception of a bat section taken from the conveyor, said positioning means comprising a recess in the table to hold a tool with its open side uppermost.

10. In apparatus of the class described, a table, a bat-holding stand adjacent one side of the table, means for sustaining a roll of endless bat on said stand, means for feeding the bat from the roll to a position over the table, said table adapted to sustain a sectional bat-containing and stuffing tool adjacent to said bat feeding means whereby an attendant may take a section of bat fed over the table and place it within the tool on the table, substantially as shown and for the purpose described.

MAURICE J. STACK.
